UNITED STATES PATENT OFFICE.

DOUGLASS G. TOMKINS, OF NEW YORK, N. Y., ASSIGNOR TO STANDARD DEVELOPMENT COMPANY, A CORPORATION OF DELAWARE.

LIQUID-DISPENSING DEVICE.

Application filed April 25, 1924. Serial No. 708,977.

To all whom it may concern:

Be it known that I, DOUGLASS G. TOMKINS, a citizen of the United States, residing at New York, in the county of Bronx and State of New York, have invented new and useful Improvements in Liquid-Dispensing Devices, of which the following is a specification.

This invention relates to liquid-dispensing devices, particularly those of a character suitable for facilitating supply of controlled amounts of lubricating oils, etc. The invention will be understood from the following description, taken in connection with the accompanying drawing, in which—

Fig. 1 is a longitudinal sectional view of the device;

Fig. 2 is a bottom view; and

Figs. 3 and 4 are enlarged sectional details.

In the drawing the reference numeral 1 designates a container, which may be made up of tin-plate or other suitable sheet material and which may vary somewhat in its precise form, but preferably will be of square or rectangular cross section, as more convenient for handling. The container is provided with a nozzle or spout 2 having an inturned or inserted flange member 3 which is shaped to form a valve-seat 4 against which may rest a valve 5 having a washer of leather, prepared fiber or other desired material. The valve is carried on the end of the rod 6 which preferably is compensating as to length, as by being provided with curvatures 7 or other means to allow of a small amount of longitudinal take-up for a purpose to be referred to more in detail hereinafter, and near the other end of the rod is a vent-valve 8 which has a sleeve extension 9 embracing the enlargement 10 on the end of the rod and thence projecting on as a tubular journal for the actuating bar 11. The end of the sleeve is enlarged or headed up to retain the actuating bar against disengagement. The vent-valve 8, as in the case of the spout-valve 5, is provided with a suitable washer face, and coacts with a valve-seat 12 internally of the vent opening. Upon the bottom of the container is a cam-like surface or ridge 13 against which the inner face of the actuating bar 11 rides, and externally of the bar 11 is an insert member 14 having a cam-ridge 15 generally parallel to the cam-

ridge 13 for engaging the outer face of the bar. The bar 11 thus rides between the two cam surfaces.

With the actuating bar 11 swung around into the diametrically-spaced depressions 16, the valve-rod 6 is carried forwardly, unseating the spout valve 5 and the container in inverted position can be filled on a suitable charging device. Similarly, in use by inverting the container and swinging the bar 11 around into the depressions 16 the oil or other liquid can be discharged to the amount desired and the valve 5 then be closed by swinging the bar 11 around in its cam-path until tight. It will be noticed that while the spout valve 5 is open the vent valve 8 is also unseated so as to allow passage of air to permit flow, but when the spout valve is drawn back against its seat the vent valve 8 is also drawn up against its seat and the container can be set upright or be placed in any position without danger of leakage at either bottom or spout. The compensation curvatures 7 in the rod 6 allow of sufficient take up either way to at all times insure the simultaneous seating of both valves.

I claim:

1. In a liquid-dispensing device, the combination of a container having a spout provided with an internal valve-seat and a bottom provided with a vent-opening, a valve seat internally of said vent-opening, a valve for coacting with said spout valve-seat, a vent-valve for coacting with the vent valve-seat, a compensating valve-rod carrying said spout-valve and having an enlargement on its other end, a sleeve extending from said vent-valve and embracing the enlargement on the end of the valve-rod, and projecting as a tubular journal, an actuating bar mounted on said journal, a cam-surface on the bottom of the container against which said bar rides with its inner face, and an insert member presenting a cam-ridge parallel to the first mentioned cam-surface for engaging the outer face of said actuating bar.

2. In a liquid-dispensing device, the combination of a container having a spout provided with an internal valve-seat and a bottom provided with a vent-opening, a valve-seat internally of said vent-opening a valve for coacting with said spout valve-seat, a vent-valve for coacting with the vent valve-

- seat, a valve-rod carrying said spout valve and having an enlargement on its other end, a sleeve extending from said vent-valve and embracing the enlargement on the end 5 of the valve-rod, and projecting as a tubular journal, an actuating bar mounted on said journal, and a cam surface carried 20 by the container bottom upon which said bar rides.
- 19 3. In a liquid-dispensing device, the combination of a container having a spout-valve and a bottom provided with a vent-opening, a valve-seat internally of said vent-opening, a valve-rod carrying said spout 25 valve and having an enlargement on its other end, a sleeve extending from said vent-valve and embracing the enlargement on the 15
- end of the valve-rod and projecting as a tubular journal, an actuating bar mounted on said journal, and a cam surface carried 20 by the container bottom upon which said bar rides.
4. In a liquid-dispensing device, the combination of a container having a spout, and a bottom vent-opening, a rod carrying a 25 vent-valve seating in the vent-opening and having an enlargement on its end near the vent-valve, a sleeve extending from said vent-valve and embracing the enlargement 30 on the end of the valve-rod and projecting as a tubular journal, and an actuating bar mounted on said journal.

DOUGLASS G. TOMKINS.
